UNITED STATES PATENT OFFICE

ROBERT B. BRANDL, OF ST. PAUL, MINNESOTA; LILLIAN BRANDL EXECUTRIX OF
SAID ROBERT B. BRANDL, DECEASED

DOOR STRUCTURE FOR GRAIN BINS OR THE LIKE

Application filed May 31, 1930. Serial No. 458,698.

It is my object to provide an improved door structure, particularly, although not exclusively, adapted for use with metal grain bins which are to be locked or sealed against unauthorized withdrawal of the contents of the bin. The invention includes certain novel features of construction for securing a simple, strong and weather-tight door.

In the accompanying drawings, which illustrate the best form of my device at present known to me, Figure 1 is a perspective view of my improved door together with fragmentary portions of the roof and walls of a sheet metal grain bin; Fig. 2 is a fragmentary, vertical section through the upper portion of the door structure; Fig. 3 is a fragmentary horizontal section taken on the line 3-3 of Fig. 2; Fig. 4 is a similar section taken on the line 4-4 of Fig. 1; Fig. 5 is a fragmentary section taken on the line 5-5 of Fig. 1 and Fig. 6 is a central vertical section through the grain withdrawal spout and adjacent portion of the door.

The invention is shown in connection with a cylindrical bin having a wall 7 and a conical roof 8 constructed from sheet metal and composed of long, relatively narrow panels connected together at their side edges. The door opening extends from top to bottom of the wall 7 between longitudinal frame members 9. Inwardly bent flanges 10 along the side edges of the members 9 engage folded edges 11 on the sheet metal wall 7 and gripping the inner surfaces of the wall 7 are angle bars 12 for securing the folded portions 11 against the flanges 10 under the action of bolts 13. These bolts are inserted through perforations in the members 9 and 12. Guide members 14 for slidable sections 15 and 16 of the door are secured to the frame members 9, as best shown in Figs. 4 and 5, the connections being preferably made by spot welding. To retain and guide the slidable sections, outer flanges 17 and inner flanges 18 are provided on the members 14. The channels thus formed extend from top to bottom of the wall 7, except that the outer flanges 17 terminate short of the upper ends of the flanges 18 to form an opening 19 into which the door sections 15 and 16 may be inserted into en-

gagement with the inner flanges 18. These door sections are moved downward in the channels between the flanges 17 and 18 to closed position.

At intervals, transverse frame members 20 extend horizontally between the frame members 9, being secured thereto by the bolts 13, as best shown in Fig. 4. The inner surfaces of these members 20 are located in a plane common to the inner surfaces of the guide flanges 17 so that the members 20 do not interfere with the free movement of the sections 15 and 16 along their guide channels. The sections are interchangeable, being of equal length and the members 20 are spaced apart a distance equal to the length of the door sections so that when the several sections are in closed position, the lines of contact 21 between them are located behind the frame member 20, as shown in Fig. 1.

To close the opening 19 at the upper end of the door, a pivot section 22 is mounted on horizontal pivot bolts 23 (Figs. 2 and 3). Elongated slots 24 are formed in the door section 22 to receive the bolts 23 and permit limited movement of said section longitudinally of the flanges 18. As shown in Fig. 1, a suitable hasp 25 is provided on the exterior of the section 22 near its lower edge to be placed in locking engagement with a U-shaped projection 26 secured to the uppermost member 20. An opening in the roof 8 has a suitable cover 27 which is removable to permit filling of the bin when the door is closed and, in one of the door sections, an outlet spout 28 is slidably mounted to facilitate the withdrawal of the grain into sacks or other receptacles. This spout 28 normally projects within the bin, as indicated in full lines in Fig. 6, and has a small sliding closure 29 adapted to be secured in closed position by a hasp 31. When the grain is to be withdrawn through the spout 28 the latter is extended, as indicated in dotted lines in Fig. 6, and the closure 29 is moved to open position.

In use, when the door sections are in closed position the bin is locked against unauthorized withdrawal of the contents by applying suitable seals and locks to the hasps on the pivoted door section 22, cover 27 and closure

29 of the spout 28. To gain access to the interior of the bin the lock and/or seal on the hasp 25 is removed and then the section 22 is raised to free its lower edge from behind the uppermost frame member 20, the slots 24 permitting this movement. When the lower edge of the section 22 is free of the member 20, said section may be swung outward to open position, as indicated in Fig. 1, and in dotted lines in Fig. 2. If a larger opening is desired, the sliding section 16 may be moved upward between the flanges 17 and 18 and then removed through the opening 19. Similarly the sections 16 and 15 may be removed.

To close the door, the above described operations are reversed. When the sliding sections are in closed position their ends abut one against another behind the transverse frame members 20, as indicated at 21, and the members 20 make a weather-tight connection between the sections. The continuous metal guide channels made weather-proof joints along the side edges of the door sections. When the pivoted section 22 is in closed position it is similarly sealed and is retained in the path of the sections 15 and 16 by the locking means which prevent upward sliding of said section out of engagement with the frame member 20. All of the door sections are preferably of hollow box form with the flanges forming their side edges extending inward from the main panel constituting the outer door surface. This gives ample rigidity and strength to the door.

Having described my invention what I claim as new and desire to protect by Letters Patent is:

40 1. In a door structure for grain bins or the like, parallel frame members extending along the sides of a door opening, inner and outer guide members extending along said frame members to receive slidable door sections between them, said outer guide members terminating a substantial distance from the ends of said inner guide members to form an end opening for the insertion and removal of the door sections, slidable door sections adapted to be moved longitudinally between said inner and outer guide members and to abut, end to end, one against another when in closed position, an end door section extending in the path of said movable sections when in closed position and movable to open position through said end opening and means for securing said end door section in the path of said slidable door sections to retain them in closed position.

60 2. In a door structure for grain bins or the like, parallel frame members extending along the sides of a door opening, inner and outer guide members extending along said frame members to receive slidable door sections between them, said outer guide members

terminating a substantial distance from the ends of said inner guide members to form an end opening for the insertion and removal of the door sections, slidable door sections adapted to be moved longitudinally between 70 said inner and outer guide members and to abut, end to end, one against another when in closed position, an end door section movable to open position through said end opening and disposed in end to end abutment with a slidable section when in closed position, a pivotal support for said end section having a pivotal axis extending transverse said frame members and means for securing said end section in the path of said slidable sections to retain them in closed position. 80

3. In a door structure for grain bins or the like, longitudinal door frame members mounted in spaced, parallel relation, transverse frame members connecting said longitudinal members at intervals, inner and outer guide members extending along said longitudinal frame members and forming continuous channels for door sections, an opening being formed in said outer guide members to permit 90 the insertion and removal of door sections, slidable door sections severally spanning the space between adjacent transverse frame members and adapted to be moved longitudinally in said channels to and from closed position, a pivoted door section movable to open position through and disposed in the path of said slidable sections when in closed position said opening and means for securing said pivoted door section in the path of said 100 slidable door sections to retain them in closed position.

4. In a door structure for grain bins or the like, longitudinal door frame members mounted in spaced, parallel relation, transverse frame members connecting said longitudinal members at intervals, inner and outer guide members extending along said longitudinal frame members and forming continuous channels for door sections, an opening being formed in said outer guide members to permit the insertion and removal of door sections, slidable door sections severally spanning the space between adjacent, 110 transverse frame members and adapted to be moved longitudinally in said channels, said sections abutting, end to end, one against another at said transverse members and the lines of contact between sections being covered by said transverse members when said sections are in closed positions, a pivoted door section movable to open position through said opening and means for securing said pivoted section in the path of said slidable sections to retain them in closed position. 120

5. In a door structure for grain bins or the like, longitudinal door frame members mounted in spaced, parallel relation, transverse frame members connecting said longitudinal members at intervals, inner and outer 130

guide members extending along said longitudinal frame members and forming continuous channels for door sections, an opening being formed in said outer guide members
5 to permit the insertion and removal of door sections, slideable door sections severally spanning the space between adjacent, transverse frame members and adapted to be moved longitudinally in said channels, said sections
10 abutting, end to end, one against another behind said transverse members when in closed positions, a pivoted door section movable to open position through said opening and means for permitting limited movement of said
15 pivoted section longitudinally of said guide members to engage the adjacent, slideable door section behind one of said transverse frame members.

In testimony whereof, I have hereunto
20 signed my name to this specification.

ROBERT B. BRANDL.
